UNITED STATES PATENT OFFICE.

JOHN E. LEIKAUF, OF BEDFORD PARK, NEW YORK, ASSIGNOR TO PARK & TILFORD, OF NEW YORK, N. Y., A CORPORATION OF NEW YORK.

DESIGN FOR A CANDY-BOX.

44,009.

Specification for Design.

Patented May 13, 1913.

Application filed October 22, 1912. Serial No. 727,246. Term of patent 3½ years.

To all whom it may concern:

Be it known that I, JOHN E. LEIKAUF, a citizen of the United States, residing at 2969 Decatur avenue, in Bedford Park, Westchester county, State of New York, have invented a new, original, and ornamental Design for Candy-Boxes, of which the following is a specification, reference being had to the accompanying drawing, forming part thereof.

The figure is a perspective view of a candy box, showing my new design.

I claim:—

The ornamental design for a candy box as shown.

JOHN E. LEIKAUF.

Witnesses:

GEORGE L. LEIKAUF,
LEWIS T. KNOX.
